UNITED STATES PATENT OFFICE

2,110,097

CONTAINER

Harry Sebell, Boston, Mass., assignor of one-half to Arthur H. Parker, Concord, Mass.

Application October 21, 1936, Serial No. 106,755

6 Claims. (Cl. 221—11)

This invention relates to cans of that type in which the top end of the can is formed with a filling opening through which the can is filled and which is subsequently sealed by means of a sealing closure.

One of the objects of the invention is to provide a can of this type with a novel sealing closure which is formed with a tear strip portion so that by tearing the tear strip portion loose from the sealing closure a pouring opening will be formed therethrough.

A further object of the invention is to provide the sealing closure of a can of this type with a tear strip portion which when torn loose from the can remains permanently connected to the sealing closure, and which when open provides a spout member or lip over which the contents of the can flow when being discharged through the pouring opening. Other objects of the invention are to improve generally cans of this type in the particulars more fully hereinafter set forth.

In order to give an understanding of the invention, I have illustrated in the drawings a selected embodiment thereof which will now be described after which the novel features will be pointed out in the appended claims.

In the drawings:

Fig. 1 is a partial sectional view of a can embodying my invention;

Fig. 2 is a similar sectional view showing the can before the sealing closure is applied to the filling opening;

Fig. 3 shows the can opened for the discharge of part or all of its contents;

Fig. 4 is a plan view of the sealing closure illustrating one type of line of weakness;

Fig. 5 is a plan view of the sealing closure after the cover member has been applied thereto and said closure is ready to be used in sealing the filling opening of the can 1;

Fig. 6 is a section on the line 6—6, Fig. 4;

Fig. 7 is a section on the line 7—7, Fig. 5;

Fig. 8 is a section on the line 8—8, Fig. 5;

Fig. 9 is an enlarged fragmentary section showing the manner of making the line of weakness illustrated in Figs. 4 to 8;

Fig. 10 is a plan view of a sealing closure having a different form of line of weakness;

Fig. 11 is a plan view of the sealing closure shown in Fig. 10 with the cover member attached;

Fig. 12 is a section on the line 12—12, Fig. 10;

Fig. 13 is a section on the line 13—13, Fig. 11;

Fig. 14 is a section on the line 14—14, Fig. 11;

Fig. 15 shows a perspective view of the cover member 14;

Fig. 16 is an enlarged sectional view similar to Fig. 7 but showing a different form of the invention.

In some respects my improved container is an improvement on or modification of the construction illustrated in my Patent No. 2,023,151, December 3, 1935.

I have herein illustrated my invention as it might be applied to a container in the form of a tin can, and 1 indicates the can body and 2 the top end of the can. The can end 2 may be secured to the body in any suitable way as by means of the double lock seam 3. The can end 15 2 is formed with a filling opening 4 through which the can is filled. The can end 2 is shown as having an upstanding flange or curb 5 surrounding the filling opening 4 to which a sealing closure 6 is crimped after the can has been filled. 20 In cans of this type the sealing closure is frequently formed at its periphery with the U-shaped portion 7 which embraces the flange 5, the inner leg 8 of the U-shaped portion resting against the inside of the flange 5 and the outer 25 leg 9 encircling the outer face of said flange 5. An hermetic or tight seal is usually formed by crimping the flange or skirt 9 to the curb 5, and, if desired, suitable packing material 10 may be deposited in the U portion 7 of the sealing closure 30 before it is applied to the upstanding curb 5.

It is also more or less common to form the sealing opening 4 near one edge of the can as illustrated in the drawings.

The construction thus far described is such as 35 may be found in cans of this type and forms no part of the present invention.

According to the present improvements the sealing closure 6 is formed with a tear strip portion designed to be torn loose from said closure 40 thereby to form a pouring opening therethrough. The tear strip portion is so made that when it is torn loose to form the pouring opening it remains permanently connected to the closure, and when in open position it forms a lip or spout 45 extending from the pouring opening and over which the contents of the can flow when being discharged from the can. This tear strip portion of the closure is indicated at 11 in Figs. 4 to 9 and at 41 in Figs. 10 to 14, and it is formed by 50 providing the closure 6 with a line of weakness along which the tear strip can be readily torn from the body of the closure. This line of weakness preferably has a general U shape so that the tear strip portion is tongue-shaped.

The line of weakness may be formed in any appropriate way. In Figs. 4 to 9 it is formed by cutting through the closure along the line 12 and then applying a thin film of solder 22 along the line of the cut, preferably on the inside of the closure, to close the slit 12. The solder 22 hermetically seals the slit in the closure, but it has less strength than the material of the closure, so that by applying sufficient force to the 10 tongue-shaped tear strip 11 the latter will be torn from the can along the line 12.

Another way of providing the line of weakness is shown in Figs. 10 to 14 wherein the closure is scored along the line 23 thereby providing the 15 line of weakness. In either case the application of sufficient force to the end of the tongue-shaped tear strip will tear it loose from the can, but because the line of weakness has a U shape the separation of the tear strip from the closure along 20 the line of weakness will provide a tongue-shaped portion which remains permanently attached to the closure but which can be swung into open or closed position, the material of the closure bending along the line 13 to permit such opening and 25 closing movement. The material along the line 13 thus acts as a hinge for the tear strip portion. The line of weakness bounding the tongue-shaped tear strip may assume various shapes and contours. In Figs. 4 and 5 it is shown as being 30 circular, except at the ends, a shape which will produce a broad tongue-shaped tear strip. In Figs. 10 and 11 the line of weakness has a shape to form a tongue-shaped tear strip which is narrowest at its tip and which has a progressively- 35 increasing width toward the base.

In order to provide for applying the necessary force to the tear strip to tear it loose from the closure along the line of weakness, I propose to secure to the tear strip a cover member 40 constructed so that it can be readily acted on by a suitable implement to apply the requisite force to the tear strip.

In Figs. 5 to 8 the cover member is indicated at 14 and it is soldered or otherwise permanently secured to the tongue-shaped tear strip, as shown at 24. For this purpose the cover member is shown as provided with an opening 30 through which the solder 24 may be applied. This cover member is also formed with a loop 50 portion 25 adapted to receive one end of a screw-driver or any other suitable implement 26, as shown in dotted lines, Fig. 1, and by which the necessary lifting or prying force can be applied to the cover member and thereby to the 55 tear strip to tear it loose from the closure. This loop 25 can be conveniently formed by slitting the cover member along the lines 35 and then striking up the slit portion from the body of the cover member to provide the loop.

60 In Figs. 11 to 14 the cover member is indicated at 21 and it is spot welded or riveted to the tear strip, as shown at 28. In this embodiment of the invention the edge 29 of the tear strip provides a lip under which the end of a suitable implement may be placed, so that by prying with the implement over the edge 7 of the closure the tear strip may be torn loose from the closure.

A different embodiment of the invention is shown in Fig. 16 wherein the cover member is indicated at 39 and it is secured to the tear strip portion 41 by means of a rivet 38. This rivet has integral therewith the extension 42 provided with a head 43. This head forms the means by which the prying force can be applied to the cover 70 and thence to the tear strip portion 41 to tear

the latter loose from the closure 6. The extension 42 also provides a knob by which the cover member and its connected tear strip may be manipulated for opening and closing the pouring opening. 5

In the construction shown in Fig. 16 the single element, i. e., the rivet 38 with its headed extension 42 provides both the means for securing the cover member 39 to the tear strip and also the means by which the prying force is applied 10 to the cover member.

The cover member is preferably somewhat larger than the tear strip portion 11, and as herein shown one edge 16 of the cover member is in substantial alignment with the line 13 along which the closure member bends when it is opened and closed, and the opposite edge 17 extends somewhat beyond the end of the tear strip. The dimensions of the cover member 14 in a direction transverse to the tear strip 11 may be 20 conveniently such that the ends 18 of the cover member fit against the inner legs 8 of the U portion 7 of the sealing closure.

Where the filling opening 4 is adjacent one edge of the can end 2 as herein shown, the sealing 25 closure will preferably be so positioned on the can end that the tongue-shaped tear strip is directed toward the center and the hinge portion 13 for the tear strip is nearest to the side of the can. 30

The can may be opened by inserting a suitable instrument, such as a screw-driver 26, through the loop 25 of the cover member, as shown in Fig. 1, and then applying a prying force to the implement in the direction of the arrow a in Fig. 35 1, or by placing the end of the implement underneath the edge or lip 29 in Fig. 13 and exerting a prying force on the implement using the edge 7 of the closure as a fulcrum, or by applying suitable prying or lifting force to the knob portion 40 42 in Fig. 16. In all cases this prying action will tear the tear strip loose from the closure along the line of weakness, thereby forming a pouring opening 19. When the tear strip 11 and the cover member are swung outwardly into their 45 open position shown in Fig. 3, said tear strip and cover form a lip or spout projecting from the pouring opening 19 and over which the contents of the can flow when being discharged.

The sealing closure preferably has a concavo- 50 convex shape with the convex face on the exterior and the cover member may be conveniently given a similar shape. With this construction, when the tear strip and cover member are in open position, the face thereof over which the 55 contents of the can flow has a concave or scoop or spout shape which prevents the stream flowing from the pouring opening from spreading and serves to guide it in its flow.

The pouring opening is preferably situated 60 close enough to the side wall of the can so that when the tear strip and cover member are in their open position they will direct the stream issuing from the pouring opening over the edge 20 of the can, as shown in Fig. 3, thereby preventing any of the contents of the can from flowing onto and soiling the end of the can. 65

If the contents of the can are of such a nature that only a portion thereof is to be discharged at any one time, then when the desired quantity has 70 been poured out of the can, the tear strip and cover member may be swung back into closed position, in which position the tear strip fills the pouring opening and the cover member 14 overlies the joint at the edge of the tear strip. The can 75

may be readily opened again in order to discharge more of its contents by simply swinging the tear strip and cover member back into the open position.

5 The can can thus be repeatedly opened for the discharge of a portion of its contents and then closed again, and while, after the first opening the can will not be hermetically sealed when it is closed, yet the cover member affords 10 a sufficient protection for the pouring opening to prevent any dirt or foreign substance from gaining access to the can.

10 It is expected that the can will be made, in the first instance, with the can end provided 15 with the filling opening as shown in Fig. 2, and that the sealing closure 6 with its line of weakness and with the cover member attached thereto will be made as a separate complete unit. After a can has been filled then a sealing closure embodying the invention is applied to the filling 20 opening to seal the can. The presence of the cover member and line of weakness does not interfere at all with the crimping of the flange 9 of the sealing closure to the curb 5 of the filling 25 opening by the crimping machines now in common use.

When the can gets into the hands of the ultimate consumer, however, he has a can which he can readily open as above described and which is 30 provided with a cover for the pouring opening.

30 While I have illustrated some embodiments of the invention, I do not wish to be limited to the constructional features shown.

I claim:

35 1. A container having in its end a filling opening, a sealing closure for sealing the opening, said closure being provided with a U-shaped line of weakness defining a tongue-shaped tear strip having its tip directed away from the edge of the container end and which, when torn from the closure, leaves a pouring opening therethrough, a cover member permanently secured to the tear strip and by which it may be torn loose from the closure, the base of said tongue-shaped tear strip 40 being permanently secured to the closure, whereby by when the tear strip is torn from the closure along the line of weakness said tear strip and the cover member may be turned back into a position with the tip of the tear strip directed outwardly from the center of the container end and into a 45 position in which said tear strip and cover form a discharge spout for the pouring opening.

50 2. A container having a filling opening, surrounded by an upstanding curb, a sealing closure for sealing said opening and provided with a U-shaped rim portion embracing the curb, the body of the closure being provided with a U-shaped line of weakness defining a tongue-shaped tear strip which is permanently secured to the closure but which is adapted to be torn loose therefrom 55 along the line of weakness thereby to leave a pouring opening, a cover member secured to the tear strip and by which the latter may be torn loose from the closure by an implement which

is fulcrumed on the marginal portion of the closure, said tear strip and cover adapted when turned into open position to form a discharge spout for the pouring opening.

5 3. A container having a filling opening in one end thereof, a sealing closure for sealing said opening, said closure being formed with a U-shaped line of weakness defining a tongue-shaped tear strip permanently secured to the closure and which, when torn from the closure, leaves a 10 pouring opening therethrough, a cover member overlying the tear strip and secured thereto and provided with a knob member by means of which a prying force may be applied to the cover member and thence to the tear strip to tear the latter 15 loose from the closure thereby to form a pouring opening.

20 4. A container having a filling opening, a sealing closure for sealing said opening, said closure being provided with a U-shaped line of weakness 25 defining a tongue-shaped tear strip which is permanently secured to the closure and which, when torn loose from the closure, leaves a pouring opening, and a cover member secured to the tear strip and overlying the latter, said cover 30 member having a loop portion to receive an implement by which the tear strip can be torn from the closure.

30 5. A container having in one end wall thereof a U-shaped line of weakness defining a tongue-shaped tear strip which, when torn from the wall, leaves a pouring opening therethrough, said tear strip having its tip directed inwardly away from the peripheral portion of the container end, a cover member permanently secured to the tear 35 strip and by which it may be torn loose from said wall, said tear strip being permanently secured to the wall and adapted, when torn therefrom, to be turned back toward the peripheral portion of the can end and into a position in which it and 40 the cover member form a discharge spout for the pouring opening, said cover member being of sufficient size to project over the edge of the container when it is in its discharge-spout 45 position.

45 6. A container having a U-shaped line of weakness in one end wall thereof defining a tongue-shaped tear strip which, when torn from the wall, leaves a pouring opening therethrough, said tear strip having its tip directed inwardly away 50 from the peripheral portion of the can end, a cover member having a concave inner face, which cover member is permanently secured to the tear strip and by which it may be torn loose from said wall, said cover member being of a size to 55 overlie the line of weakness and said tear strip being permanently secured to the wall and adapted, when torn therefrom, to be turned back toward the peripheral portion of the can end and into a position in which it and the cover member 60 form a dished discharge spout for the pouring opening.

HARRY SEBELL.
